ERNEST B. THURSTON, OF TOLEDO, OHIO, ASSIGNOR TO THE HAUGHTON ELEVATOR & MACHINE CO., OF TOLEDO, OHIO, A CORPORATION OF OHIO.

CONTROL MECHANISM.

Application filed November 12, 1921. Serial No. 514,584.

This invention relates to the control of electrically operated equipment.

This invention has utility when incorporated as an elevator controller equipped with an alternating electric current drive, having advantages for smoothness of operation at high speeds, especially in ranges above 250 ft. per minute, and even up to elevator speed maxima, the connections operable to effect gradual and quick pick-up on high speed with quick but gradual stopping obtained by having the control connections through the low speed.

Referring to the drawings:

Fig. 1 is a wiring diagram of an embodiment of the invention in a two-phase four-wire alternating electric current installation for elevator service;

Fig. 2 is an across-the-line analysis of the installation diagram of Fig. 1, the reference characters in parentheses indicate the operator for the switch adjacent which said reference character is placed; and

Fig. 3 shows motor operation curves hereunder.

In elevator shaft 1 are landings 2 for elevator car 3 in its travel as actuated from hoist line 4. This hoist line 4 extends from the car 3 upward about drum 5, and thence about idler 6 to counterweight 7.

Considering the wiring lay-out, power supply lines 8, 9, complete a phase, while lines 10, 11, are the power supply lines completing the other or second phase of the two-phase four-wire alternating current supply. The various safety devices and their interconnection with the controller are herein shown as in the phase supplied by the lines 8, 9.

The power supply line 9 has branch line 12 extending to emergency switch 13 on the car 3, located within reach of the operator of the car, and normally closed. From this emergency switch 13 on the car 3, extends line 14 to switch 15, closed when the car carried doors are closed and open when such doors are open, say at a landing. From this door interlock switch 15 line 16 extends to switch 17, opened by speed governor 18 driven by line 19 from the car 3 when the

travel of the car 3 exceeds the speed or travel rate for which the governor is set. The door interlock switch 15 is shown opened by car door 20.

The speed controlled switch 17 has line 22 therefrom to upper overtravel switch 23, normally closed, and thence by line 24 to lower overtravel switch 25, also normally closed. From this switch 25, line 26 extends through landing door interlock switches 27, open if any landing door 28 be not closed; thence by line 29, resistance 30, through slow speed main switch coil 31 of slow speed main switch 32. Leading from this coil 31 is line 33 to interlock 34 at main high speed switch 35. With this switch 35 not thrown, the interlock 34 is closed, so that the line 33 is connected to line 36 extending to switch 37 as an interlock at down direction switch 38. This interlock 37 has the line 36 thereto also connected by line 39 to interlock 40 at up direction switch 41. These interlocks 37, 40, are open until the controller has operated to determine the direction the elevator car 3 is to travel. This means the slow speed main switch 32 has one side of the line to the coil 31 open until the direction for car travel has been determined. Furthermore, due to the interlock 34, even though the direction switch selected be thrown for energizing the coil 31, such coil is deenergized when the main high speed switch 35 is closed.

The slow speed main switch 32 has been described as connected into the control system herein disclosed between the power supply and interlocks on the direction switches 38, 41. The coil for releasing the motor shaft is also connected by interlocks for operation as a direction switch is thrown. To effect this sequence of control, the line 29 has branch 42 to interlock 43 at the down direction switch 38, and said interlock is open as this direction switch 38 is open. Line 44 from the line 42 extends to interlock 45 at the up direction switch 41. This interlock 45 is also open when the up direction switch 41 is open. When the up direction switch 41 is closed, the interlock 45 connects the line 44, through this interlock

with line 46 extending back to the side of the interlock 43 away from the line 42 thereto. Accordingly with either direction switch 38 or 41 closed, an interlock connects 5 to line 47 and thence to coil 48 at brake releasing switch 49.

From this brake switch coil 48, line 50 extends to central terminal 51 engaged by contact 52 of controller 53 in the car 3. For up- 10 direction travel of the car 3, the controller 53 has its upper end rocked to the left, shifting the contact 52 first to connect the terminal 51 with terminal 54 of line 55 to upper normally closed limit switch 56, thence 15 by line 57 to the interlock 37 at the down direction switch 38. With this switch 38 open, the interlock 37 is in position for connecting the line 57 with line 58 extending to normally closed upper overtravel switch 20 23, and thence by line 59 past lower overtravel switch 25, also normally closed. From this switch 25, the line 59 is connected by line 60 to the main power supply line 8. The safety devices are all in series as to the 25 phase of current supply from the lines 8, 9, but such circuit is open, due to the interlocks at the direction switches being both open.

Shifting of the controller 53 to have its 30 contact 52 engage terminal 61 permits flow of the first energizing circuit from the supply line 8 by way of line 62 to energize coil 63 at the up direction switch 41. The other side of the coil 63 is connected by line 64 and the line 42, to the line 29, in communication with the supply line 9. The controller contact 52 is connectable for communication with the supply line 9.

This energizing of the up-direction switch 40 coil 63, effects throwing of this switch 41, so positioning the interlock 45 that the lines 44, 46, 47, energize the coil 48 to throw the brake releasing switch 49. Branch line 65 from the power supply line 8 extends to this switch 49, and as this switch is closed is connected to line 66 to brake coil 67, thence by line 68 completing circuit to the supply line 9. Simultaneously branch line 69 from the supply line 11, extending to the 50 switch 49, is connected to line 70 to brake coil 71, having line 72 therefrom to the power supply line 10. The switch 49 has thus served to energize both coils 67, 71, of the brake for operating brake shoes 73 against the holding action of spring 74, to release brake drum 75 on shaft 76 so that motor 77 may be operated to drive the drum 5 for effecting elevator car travel in up direction. As this up-direction switch 41 is thrown to closed position, the interlock 40, has connection with the line 62, by way of the lines 39, 36, the interlock 34 at the main high speed switch 35 and thence by the line 33, to energize the coil 31 at the switch 32. 55 This slow speed main switch coil is ener-

gized inasmuch as the line 33 is thus connected to the supply line 9, while the line 62 is connected to the supply line 8.

The control of the power lines as brought about by closing the switch 41 for up-direction travel, may now be considered. The power supply line 9 has branch 79 to the down direction switch 38, and line 80 therefrom to the up-direction switch 41. This line 80 is connected by the closing of this 75 switch 41 to the main slow speed switch 32, by line 81. The power supply line 8 has branch 82 to the up-direction switch 41, connected by the closing of this switch 41, to line 83 extending to low speed winding 84 80 and to high speed winding 85 for the motor 77.

The power supply lines as controlled by the main slow speed switch 32 connect the resistance for slow speed starting of the 85 motor 77. The power supply line 10 has branch 86 to this switch 32, while the other side of this phase has connection from the power supply line 11 by way of line 87 directly to the windings 84, 85, at the motor 90 77. As this main slow speed switch 32 is closed, it connects the line 81 by line 88 through resistances 89, 90, and line 91 to the slow speed winding 84 for completing the 95 phase therewith as to the line 83. The closing of this slow speed switch 32, connects the line 86 to line 92 through resistances 93, 94, and by way of line 95 to complete the second phase with the line 87 at the slow speed winding 84 for the motor 77. The 100 motor 77 is accordingly fully connected up for starting, and its shaft 76 is released to permit such starting for moving the car 3 upward.

The acceleration of the slow speed operation of the motor 77 is brought about automatically after the main slow speed switch 32 is closed. From the line 69 at the brake releasing switch 49 extends line 96 to coil 97 at slow speed accelerating switch 98, and from thence by way of line 99 to the line 92 at the switch 32. The slow speed accelerating switch 98 is accordingly thrown immediately the switch 32 is thrown. The throwing of this switch 98 cuts out resistor comprising resistances 89, 93, as the motor 77 is getting under way for more rapid building up of the starting of this motor 77. However, the resistor comprising resistances 90, 94, is left in as current modifying means. 115 120 125

The starting of the motor 77, as herein described has been by step by step shifting of the controller 53. In practice, more especially in passenger elevator service, the shifting of the controller 53 is so rapid that actually there is not slow speed winding operation for starting the motor 77, but the starting is on high speed with the automatic acceleration therefor. Accordingly the shifting of the controller 53 to have its con- 130

tact 52 engage terminal 100 brings about control connections as usual for quick acceleration in starting the car 3.

The high speed point or terminal 100 at 5 the controller is connected by line 101 past normally closed upper limit switch 56, thence by way of line 102 to the interlock 34 at the main high speed switch 35. As this interlock 34 is open to the line 102 until this switch 10 35 is closed, there is no control action as yet in this line. The line 102, has branch 103 to interlock 104 connected in the torque motor automatic high speed acceleration control. As the torque motor is not started, this in- 15 terlock 104 is closed and there is permitted current flow to the line 103, by way of line 105 extending to line 106 on the same side of open interlock 34 as the lines 102, 103. This line 105 has branch line 106 to main 20 high speed switch coil 107, at the switch 35, with line 108 therefrom to the lines 42, 29.

The completion of the circuit through the coil 107, in throwing the main high speed switch 35, operates the interlock 34 for de-en- 25 ergizing the main slow speed switch coil 31, insuring that such switch 32 is open. This shifting of the interlock 34, shorts the energizing circuit for the coil 107, from the line 102 to the line 106, thereby making the con- 30 tinued holding of this switch 35 closed inde- pendent of any position the interlock 104 may now assume. This interlock 104 at the acceleration mechanism for the high speed motor connections, insures that such acceleration devices are in the starting position be- 35 fore the high speed main switch 35 is thrown to closed position.

The closing of this main high speed switch 35 controls power supply current by way of 40 lines 109, 110, respectively from the lines 86, 81, on the supply side of the switch 32. The line 109 is connected by closing the switch 35 with line 111 through resistor comprising resistances 112, 113, 114, and line 115 to com- 45 plete a phase with the line 87 at the high speed winding 85 for the motor 77. Simulta- neously, the line 110 is connected through line 116, resistor comprising resistances 117, 118, 119, and line 120 to complete the second 50 phase of the two-phase energizing current for the high speed winding 85 of the motor 77 with the line 83.

From the line 111 is branch 121 extending to windings 122 of torque motor 123, com- 55 pleting the first phase for this motor by way of line 124 as a branch of the line 11. The line 116 has a branch 125 to the second winding of the windings 122 for the torque motor 123. The phase of this second winding is 60 completed by line 126 as a branch of the line 83. It will thus be seen that immediately the main high speed switch 35 is closed, energizing current is supplied for starting the torque motor 123.

65 This torque motor 123 is operable as a ro-

tating magnetic field type of electromagnet with travel limited to slightly less than 360°. The driven structure is so designed that the sequence of operations may occur regardless of the direction of the shifting of this motor 70 123. This is a factor of importance, for when the controller 53 is shifted to have its contact 52 engage the terminals 127, 128, 129, corresponding for down direction driving of the elevator car 3, with the up direction driv- 75 ing control terminals 54, 61, 100, respectively, there is reversal of phase relations in the energizing of coil 130 at the down direction switch 38.

Accordingly, regardless of the direction of 80 operation, the torque motor 123 rotates shaft 131, and through speed reduction gearing 132 gives shaft 133 carrying disk 134 with lug 135, a travel of slightly less than 180° as determined by stop 136. A lag or controllable 85 time interval for this operation of the rotary electro-magnet or torque motor 123 is brought about by connection 137 from the disk 134. This flexible connection 137 ex- tends to weighted piston 138 as a recover- 90 travel centering or idle positioning finding device for the shaft 133. This piston 138 is guided in its travel by cylinder 139 having leakage control adjustable valve 140, varying the retarding action in this dashpot assem- 95 bly.

As the shaft 133 starts to operate, cam 141 throws switch 142, not only opening the interlock 104, but by branch lines 143, 144, re- 100 spectively from the lines 111, and 116, connects by lines 145, 146, to cut out resistances 112, 117. In the starting of the motor 77, there is thus an automatic cutting out of acceleration resistance for aiding in rapid pick- 105 up of the motor 77 in coming up to speed.

Further rotation of the shaft 133, through cam 147 closes switch 148, effective through lines 149, 150, to cut out high speed acceleration resistances 113, 118. Thereafter, the continued rotation of this shaft 133, throws 110 cam 151, closes switch 152, and through lines 153, 154, cuts out the last resistances 114, 119, of the high speed acceleration for the motor 77.

Assuming the motor 77 has a normal speed 115 for operation of 900 R. P. M., the automatic feature herein for adequately handling the stopping of the equipment smoothly, may be thrown in say at 200 R. P. M. The motor 77 as described, while two-speed in its windings 120 and control connections, may be started directly on high speed, even at all times, should such be desired. The slow speed worked out in the automatic control connections herein, has peculiar advantages in slowing 125 down and stopping.

By throwing the controller 53 from the position with the contact 52 engaging the terminal 100, back so that the contact 52 is clear of the terminal 100, but still engages 130

the terminals 61, 54, while the motor 77 is still running above 200 R. P. M., there may occur an automatic braking or slowing down of the motor 77 independently of any release 5 of the brake shoes 73 for gripping the drum 75. As this is a speed control feature, a governor is connected up for some of this control operation. As this speed retarding action is not mechanical in applying the 10 brake shoes 73 for wear, it is a feature of importance in installation upkeep, even as a safe-guard for insuring first slowing down of the motor; for if the controller 53 be thrown into reverse travel selection direction, this slow-down first occurs before power current is supplied for such reverse direction of travel, thereby avoiding excessive current consumption at the motor. 15 This braking occurs by throwing the electric current into the slow speed windings 84, with the acceleration resistances 89, 93, out, but the permanent resistances or motor slowing down current modifying means 90, 94, in. The speed of the motor 77 being above 20 that for which the slow speed motor is designed, said latter speed say being 150 R. P. M., the electric current through the windings 84, brings about a most effective retarding generator action, electrically loading the 25 equipment for slowing down. The operation is an over speed propulsion of the motor beyond the synchronous speed of the windings 84. In order that such may not be too abrupt at the outset and may build up a little as a cushioning effect, the resistances 90, 94, as permanently in series with the windings 84, may be proportioned to the mass and speed of the moving parts. This is a 30 factor permitting accurate adaptation of 35 alternating current electric motors of a commercial design to a wide range of installations.

With the controller 53 off the high speed terminal 100, the main high speed switch 35 opens, and the interlock 34 falls to have the main slow speed switch 32 closed. The torque motor 123 is de-energized, and the weight 138 resets the shaft 133, opening the switches 142, 148, 152, and closing the interlock 104. As the controller 53 has its contact 52 only off the terminal 100, but still engages the terminal 61, the brake coils 67, 71, are still energized, and the beyond synchronous speed braking action of the windings 84 is thus far doing all the work of slowing down.

Should the controller be shifted back away from the terminal 61, and off the terminal 54, the brake coils 67, 71, are de-energized, and the brake switch 49 is opened. The interlock 40 holds the up direction switch 41 in as long as the switch 156 is closed. If this shifting of the controller 53 occurs before the motor 77 is down to a speed of say 200 R. P. M., the coils 31 and

63 are not de-energized. The circuit from the line 9 through the safety devices, including the emergency switch, car door switch, car travel governor switch, upper and lower overtravel hatch limit switches, 70 and landing door interlocks to the lines 29, 30, through the coil 31, thence by the line 33, through the interlock 34, to line 155 as a branch of the line 36, while from the line 29 to the line 42 there is connection of the coil 63 by way of the lines 62, 78, the interlock 40, and the lines 39, 36, to switch 156 held closed by governor 157 on the shaft 76 as long as such shaft is rotating at a speed above that selected for the throwing out of 80 this switch 156, and herein taken as an example as 200 R. P. M. From this switch 156, as in an auxiliary control means having a speed responsive device actuator therefor, extends line 158 past normally closed 85 down limit switch 159, thence by line 160 past normally closed upper limit switch 56, by line 161 to the line 58, connecting through the overtravel switches with the line 60 to the line 8.

There is accordingly a holding of the switch 32 in closed position at all times when the controller 53 is shifted toward or past elevator car stopping position off the high speed terminal, so long as the motor shaft 76 is rotating in excess of the 200 R. P. M. for which the speed responsive switch 156 is set to open. So, whether or not the controller 53 be only just off the high speed terminal, or back to neutral central position, the above synchronous speed braking of the shaft 76 by the slow speed windings 84 automatically occurs, with the permanent resistances 90, 94, in. The switch 156 is accordingly operable independently 100 of the controller 53. The action of this switch 156 is such that at all slowing down or stopping operations, the higher travel speeds are retarded. Inasmuch as the holding action of brake shoes is inversely proportional to the speed, the greater wear regions in control may be handled exclusively by the generator action of the slow speed windings when the operation is above the synchronous speed thereof, or instead of 110 being exclusive, for the more rapid, but still smooth stopping, there may be supplementing of such electrical braking by mechanical braking action of the shoes 73 upon the drum 75 as forced by the spring 74. As the speed of the shaft 76 falls below 200 R. P. M., the switch 156 opens, and the coil 31 is de-energized, opening the switch 32, thereby cutting out the windings 84. The final slowing up of the motor 77 is accordingly 115 handled solely by the brake spring 74. While the motor 77 is operating in the range of the higher synchronous speed of the windings 85, but with such windings cut out, due to the controller position, or the operation 120

125

130

of some stopping device, the action of the switch 156 in holding the windings 84 in for generator braking action, builds up such braking action as the motor 77 slows down, due to the permanent resistances 90, 94.

For illustrative purposes, reference may be had to Fig. 3 having speed ordinates and torque-distance abscissæ. Curve 163 indicates the torque-speed curve of the motor 77 connected up for slow speed starting with line voltage on the windings 84 and no resistance in series, that is, without permanent resistances 90, 94. Curve 164 is the torque-speed characteristic of such slow speed motor operating as a generator or acting as a brake from the high-speed operation of the motor down to the slow speed operation. The bow in this curve away from the ordinate indicates that there is a building up or increase in this braking action as the speed decreases from the high speed maximum, and such bow, introduces a cushioning in this braking action for stopping the elevator. With the introduction of the resistances 90, 94, in series with the slow speed windings 84 of the motor 77, the harshness of the curve 164 is further modified to approximate curve 165. Accordingly these resistances tend to lessen the torque. These resistances 90, 94, are held in together with the windings 84 by the speed control or automatic switch 156 controlled by the governor 157 as long as the shaft 76 is rotating above 200 R. P. M., even though the controller 53 be shifted to central off position.

If the controller 53 be shifted only to cut out the high speed motor windings 85 by moving off the terminals 100 or 129, that is, back to the terminal 61 or to the terminal 128, the brake coils 67, 71, remain energized and the slow speed motor with its windings 84 in series with the permanent resistances 90, 94, acts alone in braking as shown by speed-distance curve 166. The further shifting of the controller 53 to the off position, as the automatic switch 156 is opened, has the brake spring 74 take hold in completing the stopping of the elevator as shown by curve 167.

When the controller 53 is shifted to the full off position from full on position, there is not only the generator braking action of the slow speed motor windings 84 as modified by the resistances 90, 94, but such is supplemented by the brake spring 74, and there is automatically effected a smooth, but even more rapid emergency braking or slowing down of the elevator car 3 as shown by curve 168.

With the holding action of the brake shoes by friction inversely proportional to the speed, the more arduous and wear-promoting range is taken by the dynamic braking of the slow speed motor. The harshness of the braking action of no resistance in the slow

speed windings is modified by the resistances 90, 94, which, in practice, are proportioned to the kinetic energy of the traveling mass, in order that the taking hold for stopping may not mean a jerk. The slow speed motor 70 design to increase the generator load as the shaft 76 slows down from the high speed, is shown by the curve 165 arching away from vertical speed ordinate 169 as the curve shows speed drop toward abscissa 170. This 75 is an additional factor in according maximum slowing up action with a cushioning at the initial taking hold upon the cutting out of the high speed motor. Taking the holding action of the brake by the spring 80 74 as one at the full speed of the motor 77 of 900 R. P. M., then upon the cutting out of the switch 156 when the motor 77 is down to 200 R. P. M., the work given such brake would be as eighty-one into four, or 85 slightly over one twentieth the work required of the brake at the full speed of the motor. In brake design, this means great economy with less wear and tear in an installation of superior smoothness of control. 90

The generator braking by the slow speed motor windings 84 is in the region above the synchronous speed for such motor, and the final slowing up of the last stages of stopping, is handled solely by the brake spring 95 74. The brake spring 74 may work in conjunction with the slow speed motor windings 84 and the resistances 90, 94, at the higher speeds, or, as held out by the controller 53, not come in until the automatic 100 control switch 156 has acted, or is about to act.

It is to be noted the torque motor for the acceleration switches is connected to the power motor for the elevator and the energizing current for the torque motor is through lines at all times directly connected with windings of the power motor independently of main line or direction switches therebetween. This connection of this rotating field 110 magnet or torque motor is directly connected to the winding of the motor even though there may be resistance between the line current supply and the windings of the power motor with the connections to the torque 115 motor as more remote from the power motor than said resistance. Therefore it follows, operation of this torque motor does not depend upon the operation of any switch between the power motor and torque motor. 120

The torque motor, as herein shown, is inoperative when supplied with a single phase, and therefore gives a protection against the failure of a switch contact in that it does not short circuit the resistance in such a failure and thus does not allow the power motor winding to be directly across the line on single phase without resistance.

The invention disclosed herein, in so far as there may be disclosure of common sub- 130

ject matter with my copending applications for United States Letters Patent, as developing into Patents 1,529,675 of Mar. 17, 1925, and 1,573,207 of Feb. 16, 1926, each filed August 23, 1919, is a continuation thereof.

What is claimed and it is desired to secure by Letters Patent is:

1. The combination with an elevator, a multi-speed alternating current motor for operating the elevator, said motor having a primary winding, a controller for the motor, a resistor for the motor in series with said primary winding, and means comprising a speed responsive switch for maintaining a short circuit across a portion only of said resistor above a predetermined speed of the motor when said controller is shifted from motor actuating to motor stopping position.
2. An alternating current electric motor having high speed windings and low speed primary windings, and a permanent resistor connected at all times and only with said low speed primary windings.
3. An elevator, a two speed alternating electric current actuator including a motor for operating the elevator, said motor having a low speed primary winding, a power supply for the motor, a permanent resistor connected at all times and only with the low speed primary winding for the motor, a controller for the motor, and means comprising a speed responsive switch and connections thereto from the power supply bypassing the controller for maintaining the low speed winding connected to the power supply when said switch is closed and the controller moved from such direction of motor running control.
4. An elevator, a two speed alternating electric current motor for operating the elevator, said motor having a low speed primary winding, a power supply for the motor, a permanent resistor connected at all times and only with the low speed primary winding, a starting resistor for the low speed primary winding, a controller for the motor, and means comprising a centrifugal speed device connected to be driven with said elevator by said motor, a switch operable by said device, and connections thereto from the power supply bypassing the controller for maintaining the low speed winding connected to the power supply when said switch is closed and the controller moved from such direction of motor running control, said means, with the controller in off position and the power supply connected to said low speed winding, being operable to cut off said power supply from the low speed primary winding and the permanent resistor before the motor stops.
5. An elevator a-motor therefor, two speed windings for the motor, an alternating electric current power supply for the motor, an electromagnetically released brake for the elevator, a controller for controlling the connection of the supply to the brake and motor, and means for supplementing the retarding action of the brake comprising a speed responsive switch and connections thereto from the power supply bypassing the controller for maintaining said current supply to the lesser speed winding when said switch is closed and the controller moved from such direction of motor running control.
6. Actuating means for an elevator comprising an alternating electric current power supply, an electric motor provided with windings for one synchronous speed and windings for a less synchronous speed, a resistor connected at all times and only with said less synchronous speed winding, an accelerating resistor for said less synchronous speed winding, and means for maintaining said current supply to said less synchronous speed winding and first resistor above synchronous speed of said less synchronous speed winding.
7. A motor, an alternating electric power supply therefor, high and low synchronous speed windings for the motor, a permanent resistor connected at all times and only with said low synchronous speed winding, an accelerating resistor for said low synchronous speed winding, control means for the motor operable for disconnecting the supply of current to the motor prior to stopping, auxiliary control means for connecting said low synchronous speed winding for generator action of the motor in stopping, cutting out said accelerating resistor and maintaining said supply to said low synchronous speed winding and permanent resistor, and a brake for completing the stopping of the motor.
8. An alternating current electric motor having a power winding, a shaft for the motor, a brake for the shaft, means normally setting the brake, electro-magnetic means for releasing the brake, a polyphase current power supply for the motor and electro-magnetic means, means for maintaining said supply to said winding during motor deceleration, and a manually operable device rendering control of the brake dependent upon said last mentioned means.
9. An alternating current motor having a power winding, a shaft for the motor, a brake for the shaft, means normally setting the brake, an alternating electric current power supply for the motor, and means for establishing dynamic braking connections between said motor and supply comprising current modifying means for the motor thereby supplementing the brake for stopping the motor.
10. In a motor control system, a motor, a

high speed winding for the motor, a second speed winding for the motor, an accelerating resistor for the high speed winding, an accelerating resistor for the second speed winding, high and second speed switches for the motor, a controller for the switches and second speed resistor, and a rotating field magnet connected on the same side of said high speed switch as said motor for controlling the cutting out of said high speed resistor.

11. In a motor control system, a motor, high and second speed windings for the motor, a permanent resistor and a starting resistor for the second speed winding, a starting resistor for the high speed winding, high and second speed switches for the motor, a controller shiftable from an off position to control the switches, and a rotating field magnet connected on the same side of said high speed switch as said motor for controlling the cutting out of said high speed resistor.

12. An elevator, a two speed alternating electric current actuator therefor including a motor having a low speed primary winding, an alternating electric current power supply for the winding, a brake for the motor, and means for establishing dynamic braking connections between the motor and supply comprising current modifying means for the motor thereby supplementing the brake for stopping the motor.

13. An elevator, a two speed alternating electric current actuator therefor including a motor having a low speed primary winding, a power supply for the motor, and means for establishing dynamic braking connections between said motor and supply comprising permanent current flow modifying means consisting of relatively fixed elements connected at all times and only with said low speed primary winding.

14. A reversible motor having terminals, alternating electric current power supply for the motor, accelerating means for the motor, accelerating switches for said accelerating means, reversing switch means for the motor, a rotating magnetic field magnet directly connected to said motor terminals independently of said switch means for operating said accelerating switches, means in addition to said magnet for operating the reversing switch means, and a controller for operating the magnet in one direction of motor operation and operating the magnet in the opposite direction in the other direction of motor operation.

15. An alternating current electric motor having terminals, low and high speed windings for the motor, direction switches for the motor, accelerating means for one of said speed windings of the motor, accelerating switches for said acceleration means, a rotating magnetic field magnet directly connect-

ed to said motor terminals independently of said switch means for operating said accelerating switches, means in addition to said magnet for operating the direction switches, and a controller for determining operation of the magnet in one direction with one direction switch and in the other direction with the other direction switch, said magnet being effective for controlling the same accelerating means in each of its directions of operation.

16. A motor having first and second main switches, direction switches, a controller shiftable from an off position to control a direction, the first main and then the second main switches, connections for the motor through the first main switch, starting resistance from the second main switch, a speed controlled switch effective when the controller is shifted from the on position for the second switch for establishing connections for generator action in retarding the motor, a rotating magnetic field magnet for controlling the cutting out of the starting resistance, rotating magnetic field magnet switch means permitting controller direct control of the second main switch, and switch means at the second main switch bypassing the magnet switch means as the second main switch is operated, said second main switch means coacting to cut out the first main switch.

17. A two speed motor, accelerating resistances for both speeds of the motor, a permanent resistance for the low speed motor operation, a rotating magnetic field magnet for cutting out the high speed resistance, and a controller for the speeds of the motor shiftable from high speed position for generator operation of the low speed motor as modified by said permanent resistance in retarding the motor.

18. A motor having a low speed connection, a first main switch therefor, accelerating resistance, a low speed acceleration switch controlled for being thrown in automatically after the first main switch, a permanent resistance for said low speed motor connection, said motor also having a high speed connection, a second main switch therefor, accelerating resistance for the high speed motor connection, a rotating magnetic field magnet for cutting out the high speed motor accelerating resistance, a controller for the motor speeds, and a switch effective with the controller thrown back from on position in such direction for cutting out the low speed connection and resistance as the motor slows down from high speed operation.

19. An alternating current electric motor and control means for the stopping thereof embodying an electromagnetic brake, a resistor insertable with the motor for thereby lessening torque of the motor, and means in-

cluding a controller for braking said motor and at will causing said electromagnetic brake to supplement the action of said torque lessening resistor.

20. An alternating current electric motor, and control means for the stopping thereof embodying an electromagnetic brake, permanent resistance and additional resistance insertable with the motor for thereby lessening the torque of the motor, a controller for the motor, and a speed device for holding the motor and permanent resistance connected during retarding operation of the motor for a decrease of the motor operative rate to a determined speed, said controller being also operable for bringing about retarding operation of said brake.

21. An alternating current electric motor, and control means for the stopping thereof embodying permanent resistance and additional resistance insertable with the motor for thereby lessening torque of the motor, a controller for the motor, and a speed device for holding the motor and permanent resistance connected during retarding operation of the motor for a decrease of the motor operative rate to a determined speed.

22. An elevator, a reversible motor therefor, high and low speed windings for the motor, an alternating electric current power supply for the motor, a brake for holding the elevator, high and low speed switches for the respective windings, a controller for releasing the brake and normally operable for connecting directly the high speed switch to the supply in establishing the high speed running condition for the elevator, and means comprising a speed responsive switch effective to provide connection for said current supply to the lesser speed winding and

maintaining such connection with the controller shifted from said running establishing condition to motor reversal position, there being connections from the controller for motor reversal rendered ineffective until 45 said speed responsive switch is opened.

23. In a control system, a motor, a line switch for the motor, polyphase power supply lines for the motor, a controller shiftable from an off position to control the switch, 50 a primary winding for the motor connected to the switch, a motor starting resistor, and a rotating magnetic field magnet having polyphase connection to said supply lines and on the same side of said switch as said 55 motor for controlling the cutting out of said resistor.

24. In a control system, a motor, high and second speed switches for the motor, a controller shiftable from an off position to control the switches, a second speed primary winding for the motor connected to the second speed switch, a motor starting resistor between the motor and the high speed switch, a high speed winding for the motor, 65 a power supply for the motor, a rotating magnetic field magnet connected on the same side of said switches as said motor for controlling the cutting out of said resistor, and means comprising a speed responsive switch 70 and connections thereto from the power supply bypassing the controller for maintaining said power supply to said second speed primary winding above a predetermined speed of said motor when said switch 75 is closed and the controller moved from such direction of motor running control.

In witness whereof I affix my signature.

ERNEST B. THURSTON.
